UNITED STATES PATENT OFFICE.

NELSON H. FOOKS, OF PRESTON, MARYLAND.

APPARATUS FOR COOKING AND COOLING IN SEALED RECEPTACLES.

Application filed March 11, 1925. Serial No. 14,805.

To all whom it may concern:

Be it known that I, NELSON H. FOOKS, a citizen of the United States, residing at Preston, in the county of Caroline and State 5 of Maryland, have invented certain new and useful Improvements in Apparatus for Cooking and Cooling in Sealed Receptacles; and I do hereby declare the following to be a full, clear, and exact description of the 10 invention such as will enable others skilled in the art to which it appertains to make and use the same.

This invention relates to an improved apparatus for cooking and cooling substances 15 in sealed receptacles, and more particularly this invention relates to an apparatus adapted to cook and cool foods in sealed receptacles by means of a single liquid medium,

The process in connection with which the 20 apparatus herein described is particularly adapted for use is more fully described and claimed in my co-pending application Ser. No. 8,842.

The object of the present invention is to 25 provide an apparatus of the character indicated of an improved and simplified character adapted particularly to economize space and increase the efficiency of the process.

30 The invention consists in the novel construction, arrangement and combination of parts, as hereinafter more particularly described and claimed.

Two sheets of drawings accompany this 35 specification as part thereof, in which like reference characters indicate like parts throughout.

Fig. 1 is a vertical cross sectional view, largely diagrammatic.

40 Fig. 2 is a vertical cross sectional view through an improved inlet nozzle.

Fig. 3 is a horizontal cross sectional view through an improved nozzle on the line indicated by 3—3 of Fig. 2.

45 Fig. 4 is an end elevation of the improved apparatus.

Fig. 5 is a plan of an upper sliding baffle plate.

50 Fig. 6 is a plan of a lower fixed baffle plate.

In accordance with the present invention, a suitable liquid container 1 is provided through which an endless conveyor 2 is arranged in association with guide pulleys 3 and can guides 4 to carry cans or similar sealed receptacles by way of a circuitous

course from the top of the container downward to a level adjacent the bottom and thence outward by way of the top, as indicated in Fig. 1 by the arrows.

Within the container 1 are positioned a plurality of vertically spaced heating units 3' which, as illustrated, may consist of a plurality of steam pipes 3 associated by headers 3', the heating units 3' being 65 each independently controlled by a suitable valve 3''.

The container is also provided with a plurality of outlet or overflow pipes 5, each of said overflow pipes communicating with 70 the container at points adjacent but below one of the heating units 3'. Each of the overflow pipes 5 is independently controlled by a suitable valve 5'.

Intermediate each heating unit 3' and its 75 corresponding overflow pipe 5 is a horizontally disposed baffle consisting of two horizontal plates 10 and 11.

The lower baffle plates 10 of each of these baffle units is fixed relatively to the container and provided with a plurality of spaced orifices 9—9. The upper plate 11 of each of the baffle units is slidable upon the lower baffle plate 10, and relatively to the container and each of these plates is provided with a suitable orifice 9, so that in operation the upper baffle plates 11 may be adjusted with respect to the lower baffle plates 10, either to bring the orifices 9 in the upper plate into register with one of the 90 orifices 9 of the lower plate or to bring the orifice 9 in the upper plate above the portion intermediate the orifices in the lower plate, by means of which operations the baffles may be adjusted as desired to either 95 constitute continuous closed baffles or baffles having orifices of greater or less extent, as may be desired, depending upon the relative relation of the orifices in the upper and lower plates.

100 This adjustment may be readily accomplished by sliding the upper baffle plates 11 as indicated which, for this purpose, are provided with rods 12, 12 which extend through the end of the container 1 through suitable 105 pack glands 25 and terminate in suitable handles 13.

A suitable liquid, such as water, is supplied to the container adjacent its bottom by means of a plurality of supply pipes 7 each independently controlled by a suitable valve 7'.

110 The supply pipes 7 are provided within

the container with an improved distributing nozzle 8 which comprises a cup-shaped member 15 having a downwardly directed flange 17 surrounding a suitable orifice in its bottom, which flange 17 is adapted to be passed through a suitable orifice in the bottom of the container 1 and to receive a supply pipe 7. A nut 9 is provided to engage the projecting end of flange 17 to secure the cup member 15.

A plurality of radially directed orifices 22 are provided in the side walls of the cup part 15 and a disk top 20 is provided adapted to be secured to the cup 15 by means of an interiorly threaded annular flange 21. The disk top 20 is substantially larger than the cup member 15 and provides an overhang 23 surrounding the cup 15 adapted to operate as a baffle and direct liquids passing outwardly through orifices 22 in a horizontal direction over the bottom of the container 1, by means of which vertical currents in the liquid are minimized.

In operation, one or more of the heating units may be utilized as desired, depending upon the depth of the heated strata of the liquid desired.

As illustrated in the drawings, the lowermost baffle is shown closed and all of the heating units are shown in use.

With this arrangement, the valve of the lowermost overflow pipe 5 is opened and the upper overflow pipe valves are closed.

Convection currents above the lowermost

baffle are relatively uninterrupted by reason of the fact that the orifices 9 of the baffles are in register, so that relatively little resistance to such currents is created. On the other hand, convection currents between the heated zone and the liquid below the lowermost baffle are substantially eliminated by means of the lowermost baffle which is closed, as illustrated.

By reason of the superposed plate baffles, it will be apparent that the depth of the container may be relatively small and the conveyor arranged in a compact manner, as illustrated, greatly economizing space.

By means of the improved nozzle structure described, vertical currents in the lower or cooling strata of the liquid are materially reduced.

What I claim is:

1. In a cooker and cooler comprising a liquid container, means for supplying heat to the container intermediate the top and bottom, means for supplying liquid to the container adjacent the bottom and means for restricting currents in the entering liquid to a substantially horizontal plane.

2. In a device of the character described, an improved liquid inlet nozzle comprising a chamber provided with a plurality of horizontally disposed outlet orifices and a top extending horizontally beyond the chamber and over said orifices.

In testimony whereof I affix my signature.
NELSON H. FOOKS.
